UNITED STATES PATENT OFFICE.

THOMAS L. TINCHER, OF CHICAGO, ILLINOIS.

ELEVATOR.

SPECIFICATION forming part of Letters Patent No. 664,983, dated January 1, 1901.

Application filed July 7, 1900. Serial No. 22,873. (No model.)

To all whom it may concern:

Be it known that I, THOMAS L. TINCHER, of Chicago, Cook county, Illinois, have invented certain new and useful Improvements in Elevators, of which the following is a description, reference being had to the accompanying drawings, which form a part of this specification.

My invention relates to elevators in which traveling hatches are carried, one series above the elevator-car and another below, closing the elevator-shaft automatically on a level with the several floors as the car ascends or descends.

One object of my invention is to close the shaft on a level with each floor with a light impervious strong fireproof hatch without imposing any substantial burden upon the elevator mechanism, thus avoiding the draft up elevator-shafts, which accelerates and communicates fire from one story of a building to another, preventing persons from falling down the shaft, and simplifying the problem of heating by preventing the escape of heat from the lower stories to those above.

Another object is to provide mechanism for automatically locking and unlocking each hatch at its proper floor without shock or jar to the car.

A further object is to provide means for holding the hatches positively in position in the shaft independent of friction by a mechanism which may be easily adjusted to chimney-shaped shafts or to shafts the walls of which have sunk out of parallel and which shall make it impossible for the hatches to jam or stick so long as an ordinary elevator-car can operate in such shaft.

A further object is to provide means for shipping and unshipping the upper series of hatches at the top of the shaft when this is desired.

With the above and other objects in view my invention consists in the novel construction, combination, and arrangement of parts to be hereinafter more particularly described, and specifically pointed out in the claims.

In describing my invention reference is had to the accompanying drawings, forming a part of this specification, wherein like letters and

numbers of reference indicate similar parts throughout the several views.

Figure 1 is a vertical section through a building of several stories, showing my device in place. Fig. 2 is a plan section on line 2 of Fig. 1. Fig. 3 is a rear elevation on line 3 of Fig. 1, showing one arrangement of the weights which operate the several hatches. Fig. 4 is a sectional view of the shaft, showing the shoes which operate the spring locking device in elevation. Fig. 5 is a horizontal section through the elevator-shaft, showing one of the hatches and the arrangement of slots. Fig. 6 is an elevation showing the upper series of hatches and the arrangement of slots therein. Fig. 7 shows the arrangement of slots in the lower series of hatches. Fig. 8 is a cross-section on the line 8, Fig. 5, showing one of my methods of constructing the hatches. Figs. 9 and 10 show my device for shipping and unshipping the upper series of hatches at the top of the shaft, Fig. 9 being a section on the line 9, Fig. 1. Fig. 11 is a cross-section of the bolt and crank along line 11 in Fig. 10. Fig. 12 shows my spring catch or locking device. Fig. 13 shows in perspective one of the stops for arresting the hatches. Fig. 14 is a cross-section on line 14 of Fig. 12. Fig. 15 is a side elevation showing one of the hatches locked in position by the spring-catch at its proper floor.

In the drawings, A denotes the elevator-car; B' B² B³ B⁴, the walls of the elevator-shaft; C' C² C³ C⁴, the several floors in the building; a, b, and c, the series of hatches below the car; a', b', c', d', the series above the car. a' is the counterbalance to hatch a, b' to plate b, c' to hatch c, &c. Each weight or counterbalance is connected to its proper hatch by cables a⁴ b⁴ c⁴, running over suitable pulleys at the top of the shaft and passing through the perforations a³ b³ c³. (Shown more particularly in Fig. 5.) These weights or counterbalances are sufficient each to lift the hatch to which it is connected and cause it to lie snugly against the buffer mechanism H' beneath the car as the car ascends. The buffer H' below and also the buffer H above the car consists of a light framework with an area sufficient to support the hatches. H and H' are fastened

to the car by the upright and downright bolts or posts $h' h^2 h^3 h^4$. The elastic cushions $i' i^2 i^3 i^4 i^5 i^6$, &c., are disposed at the corners of the framework and at intermediate points 5 thereon.

1 and 2 are guide-tracks on the walls B^2 and B^4 , sliding in slots 3 and 4 of each hatch.

$D' D^2 D^4$ are three of four rounded or tapering shoes fastened to the car, two on each 10 side, in such a way as to project upward and downward from the floor-level of the car approximately parallel to the walls of the shaft, tapering or deflected inward at their ends and adapted to pass freely through the slots 5, 6, 15 7, and 8 of each hatch, as shown in Figs. 4 and 5. Besides operating the spring locks or catches, as hereinafter shown and described, these shoes serve to hold the lower series of 20 hatches in perfect position in the shaft and tend to prevent sticking or jamming.

On the walls B^2 and B^4 on a level with each floor of the building are the series of stops $x x'$ and the series $y y'$, so disposed that at a 25 level with any given floor the pair $x x'$ are slightly nearer together and each nearer the medial line of the wall B^2 than the pair $x x'$ on the floor below, and the same is true of the series $y y'$ on the wall B^4 .

As the lower series of hatches rises with 30 the car, impelled by the counterbalances $a^2 b^2 c^2$, the hatch a is arrested by the stops $x x'$ and $y y'$ at the level of the floor C^2 , while the hatches b and c , being slotted at 9 and 10 next to the wall B^2 and also at 11 and 12 next to the 35 wall B^4 , avoid this set of stops; but the slots 9 and 10 and 11 and 12 of hatch b , not being in alinement with the set of stops $x x'$ and $y y'$ on the floor C^2 , since the stops $x x'$ are slightly nearer than the stops at C^2 to the medial line 40 of the wall B^2 and $y y'$, the medial line of B^4 , plate b , is therefore arrested at the floor C^2 , the hatch c avoiding this second set of stops by reason of the greater lateral enlargement of slots 9 and 10 and 11 and 12 of said hatch. 45 In this manner each hatch will be stopped at its proper floor only. While I have shown in my drawings only three hatches in the lower series, a greater or less number will be used according to the number of floors in the 50 building.

Figs. 12, 14, and 15 show in detail my locking device, a front elevation of the same on the wall B^2 appearing in Fig. 1. This locking device or spring-catch is set into the walls 55 B^2 and B^4 on a level with each floor. I prefer to use four catches to each floor. In Fig. 12, e' is the operating-arm of the spring-bolt G' , rounded or mounted with a roller f' at its end, and normally held in projection into the 60 shaft and into a portion of the path of the shoe D by the spring F' . The supporting-arm g' is also held normally in projection into the shaft by the spring F' , but does not enter the path of the shoe D . Catch E is adapted 65 to be countersunk and fastened on the walls of the shaft by means of the casing and screw-plate shown in Fig. 12.

The elevator-car is operated in the ordinary way by cables and pulleys, as shown in Figs. 1 and 2, and as it rises the lower series 70 of hatches, carried by the weights $a^2 b^2 c^2$, will follow until floor C^2 is reached, when the first set of stops $x x'$ and $y y'$ will take off hatch a , as heretofore described, and allow b and c to pass, while bolts $G' G^2 G^3 G^4$ 75 (which, by reason of the engagement of the tapering or rounded tops of the shoes $D' D^2 D^3 D^4$ with the arms $e' e^2 e^3 e^4$, have been pushed back out of the shaft) will be thrown into normal position by springs $F' F^2 F^3 F^4$ as 80 soon as the shoes $D' D^2 D^3 D^4$ pass and will engage the hatch a , thus locking it securely in place on a level with floor C^2 . In the same manner the stops and catches on succeeding floors will arrest and lock their proper hatches. 85 In Fig. 1 I have shown hatch a' closing the garret of the shaft. As the car rests on a level with the top floor C^4 , the upper series of hatches are stacked in series $b' c' d'$ upon the elastic buffer H and the lower series of 90 hatches locked, each at its proper floor, by catches $E' E^2 E^3 E^4$. As the car descends, the shoes $D' D^2 D^3 D^4$, passing through slots 5, 6, 7, and 8 of the top hatch of the lower series, engage with the rollers $f' f^2 f^3 f^4$ on arms $e' 95 e^2 e^3 e^4$, springs $F' F^2 F^3 F^4$ are forced back, the bolts $G' G^2 G^3 G^4$ release the hatch, and the descending car forces it downward on the elastic buffer H' . In a similar manner the hatches below are released and forced downward into the bottom of the shaft. Each one of the upper series of hatches avoids the spring-catches by means of slots 5 6 7 8 in alinement therewith. Each is guided by tracks 1 and 2, sliding in slots 3 and 4, descends 105 by gravity, and is forced up by the elevator-car. The stops $x x' y y'$ on floor C^5 arrest and support from below hatch a' , which hatches b' and c' pass by means of slots 9 and 10 and 11 and 12, the slots on hatch b' being narrower than those on hatch c' . The system of slots in the upper series is similar to the system in the lower series, and each hatch is arrested and held at its proper floor by the stops $x x'$ and $y y'$, there being no necessity to lock 115 these hatches in position, as they are not counterbalanced, but raised by the car and lowered by gravity.

When it is desired to carry lumber or other freight projecting above the top of the car, 120 the upper series of hatches may be held at the top of the shaft by means of the device shown in Figs. 9, 10, and 11, in which k is a lever pivotally mounted at l , and m and m' link connections to cranks $o o'$ on shafts p and p' . 125 Upon shafts $p p'$ are arms q similar to cranks o and o' and positioned similarly on the shafts. By operating handle-bar k the shafts are oscillated, throwing the arms q in the direction indicated by the arrow in Fig. 11. In Fig. 11 130 the casing J incloses the plunger r , recessed at s , in which recess the free end of arm q is in engagement, casing J being suitably slotted to provide free movement of arm q . Casing J

is provided with side walls *t*, through which the shaft *p* passes and between which the arm *q* is confined, the face-plate being preferably countersunk and held in position within the wall *B*² or *B*⁴, as the case may be, by screws, as shown in Fig. 11. By this construction the plungers *r* *r*² *r*³ *r*⁴ on the walls *B*² and *B*⁴ can be thrown by turning the handle-bar *k* to project into the shaft beneath the lowest of the upper series of hatches and the framework of buffer *H*.

The hatches which I use in my device I prefer to construct of perforated steel riveted to a steel framework, lined beneath with asbestos and held against the perforated plate by a wire mesh, as shown in Fig. 8.

Having thus described my invention, what I claim as new, and desire to secure by Letters Patent, is—

- o 1. In combination with an elevator-car and an elevator-shaft, a series of traveling hatches adapted to be carried by said elevator-car and to close said shaft at the different floors, an elastic buffer on the bottom of the car, counterbalances for normally holding said hatches against the bottom of the car, a series of stops on opposite walls of said shaft at successive levels, the stops at the successive floors being out of vertical alinement, said hatches having a series of slots in line with the stops which a given hatch is designed to pass, but not in line with the stops at the floor it is designed to close, shoes extending upward and downward and tapered at their ends, a series of locking devices having arms adapted to be pressed out of the path of the car by said shoes, each arm being adapted to release said locking devices when the elevator-car has passed, and springs throwing said devices

into engagement with the hatches at their respective floors, whereby a hatch is securely locked at its proper floor.

2. In combination with an elevator-car and elevator-shaft, a series of stops on opposite walls of the shaft at successive floor-levels, a series of traveling hatches adapted to be carried by the elevator-car, each of such dimensions as to approximately close the elevator-shaft and having slots in vertical alinement, shoes extending upward and downward and tapered at their ends mounted on said elevator-car in vertical alinement with said slots and adapted to pass therethrough, locking devices on successive floor-levels having an operating-arm in vertical registration with said slots and adapted to be retracted by said shoes, thereby releasing the lock for the purposes described.

3. In combination with an elevator-car and elevator-shaft, a shoe on said car, a series of hatches adapted to be carried with said elevator-car, having therein slots in alinement with said shoe; a series of locking devices mounted on opposite walls of said shaft at successive floor-levels, each consisting of a bolt with two arms of unequal length, the longer arm being in alinement with the said shoe, the shorter arm being out of alinement with said slots and adapted to engage said hatches, and a spring for projecting said bolt, said spring being adapted to be retracted by said shoe acting upon said longer arm, thereby unlocking the plate, for the purposes described.

THOMAS L. TINCER.
